(57) **CLAIM**

The ornamental design for an X-ray imaging apparatus, as shown and described.

DESCRIPTION

FIG. 1 is a top, front and left side perspective view of a medical X-ray imaging apparatus showing my new design; FIG. 2 is a top, rear and left side perspective view thereof; FIG. 3 is a front elevational view thereof; FIG. 4 is a rear elevational view thereof; FIG. 5 is a top plan view thereof; FIG. 6 is a bottom plan view thereof; FIG. 7 is a left side elevational view thereof; FIG. 8 is a right side elevational view thereof; and, FIG. 9 is a top, rear and left side perspective view thereof, showing a state that an electronic cassette is put in a housing section such that the electronic cassette is charged. The broken line portions of the X-ray imaging apparatus throughout the drawings are shown to illustrate environment only and form no part of the claimed design. The dash-dot broken lines in FIGS. 1 and 5 to 8 define the bounds of the claimed design and form no part thereof.
